UNITED STATES PATENT OFFICE.

ELEANOR A. HURLBUTT, OF PARRISH, WISCONSIN.

FASTENER.

Application filed February 27, 1923. Serial No. 621,621.

To all whom it may concern:

Be it known that I, ELEANOR A. HURLBUTT, a citizen of the United States, residing at Parrish, in the county of Langlade and State of Wisconsin, have invented certain new and useful Improvements in Fasteners; and I do hereby declare the following to be a full, clear, and exact description of the invention, such as will enable others skilled in the art to which it appertains to make and use the same.

The primary object of this invention is the provision of a garment fastening designed to replace the ordinary hook and eye and which, in practice, will not tear the garment or come apart casually and which by proper manipulation may be easily and conveniently engaged and disengaged. While the fastener is intended primarily for garments, it is to be understood that it is adapted for various uses where buckles, snap fasteners and the like are generally employed.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a detail view of a fastener embodying the invention, the members being engaged.

Figure 2 is a view similar to Figure 1, the members being separated.

Figure 3 is a detail view showing the first step in the operation of engaging the members, and

Figure 4 is a view showing the second step in the operation of engaging the members, the third and final step residing in bringing the two members into substantially the same plane.

Corresponding and like parts are referred to in the following description and designated in the several views of the drawings by like reference characters.

The fastener comprises complementary members 1 and 2, each consisting of a plate adapted to be attached to the part to which

the fastener is to be applied. As shown, each of the plates is provided with openings 3 to receive stitching whereby the fastener is sewed to a garment. The member 1 is provided with an elongated opening 4 having a relative transverse arrangement. A slit or narrow opening 5 extends outwardly from the elongated opening 4 through the outer edge of the plate and provides a passage for the neck portion 6 of the member 2. The passage 5 is disposed midway the ends of the elongated openings 4 and provides for the coupling and the uncoupling of the parts comprising the fastener.

The member 2 is provided with a centrally disposed neck portion 6 and cross-head 7 which projects an equal distance upon opposite sides of the neck 6. The neck 6 is of greater width than the passage 5 to prevent its movement therethrough when the members 1 and 2 are disposed substantially in the same plane. The neck 6, however, is sufficiently thin to pass readily through the passage 5 when the member 2 is disposed in a plane perpendicular to the member 1 and at a right angle thereto, as indicated most clearly in Figure 3. After the neck portion 6 of the member 2 has been passed through the narrow passage 5, the member 2 is given a one-quarter turn to bring the crosshead 7 in line with the elongated opening 4, as indicated most clearly in Figure 4. The two members 1 and 2 are disposed relatively at a right angle to each other and movement of the member 2 to bring it substantially in the plane of the member 1 completes the engagement of the parts comprising the fastener as indicated most clearly in Figure 1. It will be understood that the fastener is not liable to become disengaged because of the precise movement necessary to uncouple the same, the action being the reverse of that essential to effect a coupling or engagement of the parts.

The outer end of the narrow passage 5 is flared to facilitate the entrance of the relatively broad snap neck 6 when positioning the latter preliminary to effecting a coupling of the members 1 and 2. The three movements necessary are quickly effected after the operation of the fastener is thoroughly understood, the movements being deftly performed both in the coupling and in the uncoupling of the parts.

What is claimed is:

1. A fastener of the character specified

comprising complemental members, one of the members having a transversely elongated opening and a narrow passage leading outwardly from the elongated opening 5 through the outer edge of the member, and the companion member having a centrally disposed neck relatively broad and thin and a crosshead at the outer end of the neck, said neck being adapted to pass edgewise 10 through the narrow passage and being prevented from disengagement by substantially a one-quarter turn of the member, the two members being subsequently brought into substantially the same plane.

15 2. A fastener of the character specified comprising complemental plates, one of the plates having a transversely elongated opening adjacent its outer edge and having a centrally disposed narrow passage leading 20 through the outer edge of the plate and the companion plate having a relatively broad neck and a crosshead at the outer end thereof, said neck being adapted to pass outwardly from the elongated opening

edgewise through the narrow passage and 25 prevented from disengagement therewith by substantially a one-quarter turn, the two plates being brought to substantially the same plane when the fastener is in operative position.

30 3. A fastener of the class described having a first member and a second member, the first member being provided with a slot and a passage leading therefrom to an edge of the first member, the second member having a neck and a fastening head disposed at an angle thereto, said passage being of less width than the neck to necessitate edgewise passage of the neck therethrough and subsequent turning of the neck in the slot 35 during the process of fastening the members together.

40 In testimony whereof I affix my signature in presence of two witnesses.

ELEANOR A. HURLBUTT.
